UNITED STATES PATENT OFFICE.

SCOTT H. HULL, OF OSKALOOSA, IOWA.

DESIGN FOR A HARNESS-DEE.

SPECIFICATION forming part of Design No. 28,145, dated January 11, 1898.

Application filed November 16, 1897. Serial No. 658,764. Term of patent 3½ years.

To all whom it may concern:

Be it known that I, SCOTT H. HULL, a citizen of the United States, residing at Oskaloosa, in the county of Mahaska and State of Iowa, have invented and produced a new and original Design for a Harness-Dee; and I do hereby declare the following to be a full, clear, and exact description of the same, reference being had to the accompanying drawings, forming a part thereof.

My invention relates to a novel design for a harness-dee or strap-guide, and is shown in the accompanying drawings, in which—

Figure 1 is a front view of a harness-dee embodying my design. Fig. 2 is a rear view of the same. Fig. 3 is an end view, and Fig. 4 is a central vertical section.

As shown in the drawings, the leading or material features of my design consist of a guide-plate A, formed with an elongated rectangular slot b, a base-plate c, having an orifice

d, and an approximately inverted-L-shaped shank e, uniting said plates. The lower arm e of this shank is vertically disposed and rises from the said base-plate c, while the upper horizontal arm e' thereof extends forwardly and terminates at the rear side of the guide-plate A, thus projecting the two plates in different vertical planes, one being disposed in advance of the other, as shown.

Having thus fully described my invention, what I claim as new, and desire to secure by Letters Patent, is—

The design for a harness-dee, as herein shown and described.

In testimony whereof I affix my signature in presence of two witnesses.

SCOTT H. HULL.
